UNITED STATES PATENT OFFICE.

HUGH M. WAGNER, OF CHATTANOOGA, TENNESSEE.

COIN-CONTROLLED MECHANISM.

Application filed May 24, 1927. Serial No. 193,880.

The present invention relates to a coin controlled mechanism adapted particularly to a gasoline vending machine, particularly of that form shown in my companion application, filed with this application, and assigned Serial No. 193,881.

An object of the invention lies in the provision of a novel slot or coin way, to prevent fraud.

Another very important object of the invention lies in the provision of a novel coin operated latch structure.

With the above and other objects in view as will appear as the description proceeds, the invention resides in certain novel features of construction and in the combination and arrangement of parts as will be hereinafter more fully described and claimed.

In the drawing:

Figure 1 is a sectional elevation of the apparatus embodying features of this invention.

Figure 2 is a fragmentary plan view showing the use of the apparatus.

Figure 3 is a sectional view taken substantially on the line 3—3 of Figure 1.

Figure 4 is an edge elevation of the coin slide way.

Figure 5 is another edge elevation thereof taken opposite to that shown in Figure 4, and

Figure 6 is a detail view showing the holding means released.

Referring to the drawing in detail, it will be seen that the coin slide way is formed by a pair of plates 5 held in spaced relation by a plurality of spacers 6, so as to form a sinuous pathway, which includes the entrance A, merging into an exit branch B, which has pivoted therein, as at 7, a weighted lever 8, the weighted end being indicated by numeral 9. The free end of the lever normally abuts a shoulder at 10. A branch C is separated from the branch A

by the lever 8, and if the coin is of the proper weight, it will swing the lever 8 so as to allow the coin to pass through the branch C, but if the coin is too light, the lever will cause it to be projected by gravity through the exit B. The branch E has an

abrupt turn as at D and then merges into diverging branches E and F, which has pivoted therebetween as at 11, a lever 12, one end of which is weighted as at 13 and normally abuts a shoulder 14. If the coin is too heavy it will rock the lever 12 and pass out through branch F, but if it is of the proper weight it will pass out through branch E. A structure 15 supports a latch 16 having a bolt 17 adapted to engage a stop 18, so as to prevent movement of the structure 15 in one direction. The bolt 17 is pivotally engaged as at 19, with a bell crank lever 20, one arm of which is long and has a hopper 21 mounted on the extremity thereof, one side of which is open. The open side is next to a shield 22 supported from one of the plates 5, so that the coin of the branch E may drop into the hopper 21 and rock the bell crank lever 20 to open the latch bolt 17 as will be quite apparent and when the hopper 21 moves below the shield 22, the coin will fall therefrom and the latch structure will return the parts to their normal position. The structure 15 is also prevented from swinging by means of a lever 25, rockably mounted as at 26 and having an offset extremity 27 to engage a member 28, on the supporting structure. This lever 25 is rocked by other mechanism (not shown). It is thought that the construction, utility and advantages of this invention will now be quite apparent to those skilled in this art, without a more detailed description thereof.

It will be apparent that changes in the details of construction and in the combination and arrangement of parts may be resorted to, without departing from the spirit or scope of the invention, as hereinafter claimed or sacrificing any of its advantages.

Having thus described my invention, what I claim as new is:

A device of the class described comprising a pair of plates, spacers between the plates forming a sinuous coin passageway therebetween including an entrance branch, merging into an exit branch and a third branch, a lever having a weighted end, means pivotally mounting the lever intermediate its

ends between the exit and third branch, said third branch having a shoulder formed therein immediately adjacent the entrance branch, with which the weighted end of the lever normally maintains the other end in abutment, said third branch merging into diverging branches, a lever having a weight end, means for pivotally mounting the second mentioned lever intermediate its ends be-

tween the diverging branches, one of which ¹⁰ is formed with a shoulder against which the weighted end normally abuts, so that the outer end of the lever prevents certain authorized coins from passing therethrough, said third branch being formed with an ¹⁵ abrupt curve intermediate its ends.

In testimony whereof I affix my signature.
HUGH M. WAGNER.
